UNITED STATES PATENT OFFICE.

ALEX ANDERSON, OF DETROIT, MICHIGAN, ASSIGNEE TO EARL HOLLEY, OF DETROIT, MICHIGAN.

MEANS FOR APPLYING LAMPBLACK TO THE SURFACE OF METAL MOLDS.

Application filed April 23, 1923, Serial No. 633,903. Renewed July 19, 1924.

To all whom it may concern:

Be it known that I, ALEX ANDERSON, a citizen of the United States, residing at 9299 Cascade Ave., Detroit, in the county of Wayne and State of Michigan, have invented certain new and useful Improvements in Means for Applying Lampblack to the Surface of Metal Molds, of which the following is a specification.

10 The object of this invention is to provide an improved means for applying a coating of lampblack to the surface of metal molds carried on a rotating table or otherwise caused to travel in a closed circuit.

15 In the co-pending application of Joseph L. Dostal, Serial No. 568,405, filed June 15, 1922, means are disclosed whereby such a series of molds may be first cleaned with compressed air and then covered with lamp- 20 black by means of a stationary flame.

25 In the co-pending application of the same inventor, Serial No. 590,913, filed Sept. 27, 1922, the burner is carried on an undulating track and is caused to rotate with the rotating molds and is automatically released and subsequently re-engaged by the next succeeding molds. In the present invention the same principles are made use of as those disclosed in the aforesaid applications but the construction is simplified and the cost of manufacture reduced.

20 Figure 1 shows a plan view of the device applied to a molding machine but only one of the pairs of molds are shown in this view.

Figure 2 is an elevation on a diametrical plane showing the mechanism, a plan view of which is shown in Figure 1.

Figure 3 is an elevation taken on the plane III—III and in the direction shown on Figure 1 and shows two molds on a rotating table.

Figure 4 shows in elevation the burner and is a view looking on the plane IV—IV of Figure 2.

In Figures 1 and 2, 1 is the burner connected by pipe 2 to the spherical support 3 which in turn is supported by seat 4. 5 is a supporting arm bolted to 4 and swinging horizontally about the center of the machine. 6 is a roller bearing bolted to 5 and supporting the arm 5. 7 is the roller running on a stationary inclined track 8. 9 and 10 are supports supporting the stationary inclined track 8. 11 is the station-

ary supporting part of the machine to which 9 and 10 are bolted, and on which 5 swings.

12 is the pivot which supports this arm 5 and turns freely on 11; 13 is the pin on 60 which arm 5 swings in vertical plane; 14 and 15 are a pair of molds between which the burner 1 is suspended; 31 is the rotating table on which these molds are mounted, 16 being the support to the mold 14 and 17 65 is a plate mounted on 16 and thus revolving with the molds, the purpose of which will be described later.

In Figures 1 and 2, 18 and 19 are bearings for the horizontal shaft 20. In Figure 70 3, 21 is a plate bolted to arm 5 and 22 is an arm keyed to shaft 20, 23 being a tension spring between arm 22 and plate 21. 24 is a dog pinned to 22 and free to move on pin 25. 26 is a pin projecting from the 75 inclined track 8 and adapted to engage with dog 24.

In Figure 4, 27 is an arm mounted and bolted to shaft 20 and 28 is an arm bolted to the burner 1 and having a pin 29 which 80 is adapted to engage with a slot in the end of the arm 27. 30 is the pipe conveying the gas to the burner 1.

Operation.—In the position in which the apparatus is shown in Figure 1 the burner 85 1 is traveling clockwise, and the molds 14 and 15 are traveling anti-clockwise. The arm 5 will re-engage with the mold 14 by means of the projection 17, while the burner 1 and the arm 5 are traveling down the inclined track 8 shown in Figure 3. When the projection 17 re-engages with the arm 5 the burner 1 will also travel in an anti-clockwise direction with the molds 14 and 15 and the arm 5 will then travel up the 90 track 8. When the arm 5 reaches the position shown in broken lines in Figure 3 it automatically escapes over the top of the projection 17 and again travels down the track 8 under the influence of gravity. 100

This is substantially the invention in its simplest and therefore preferred form. The link 27 which pivots about the oscillating shaft 20 merely provides for a slight swinging motion of the burner to increase the uniformity of distribution of the flame and may well be omitted, where simplicity and cheapness of construction is of importance. A stationary pin 26 supported by the track 8 engages with the projection 24 rocking 110

the pin 24 around the fulcrum 22 which thus gives a slight rocking motion to the burner 1. A spring 23 returns the burner to its mid position as shown in the Figure 1.

5 What I claim is:

1. In a molding machine, a moving series of molds adapted to be opened, a burner adapted to pass between and to deposit lampblack upon said open molds, a radial arm 10 supporting said burner, an inclined track supporting said radial arm, automatic means whereby said burner is carried forward with each of said molds, automatically released and subsequently re-engaged by the next succeeding mold, a stationary pin engaging with said swinging burner and adapted to impart thereto an oscillating motion.
- 15 2. In a molding machine, a moving series of molds adapted to be opened, a swinging burner adapted to pass between and to deposit lampblack upon said open molds, a

radial arm supporting said burner, an inclined track supporting said radial arm, automatic means whereby said burner is carried forward with each of said molds, automatically released and subsequently re-engaged by the next succeeding mold, a stationary pin engaging with said swinging burner and adapted to impart thereto an oscillating motion.

3. In a molding machine, a moving series of molds each of which is opened for a predetermined period of time, a burner adapted to pass between said open molds, means for causing the burner to travel with each mold through a portion of its travel and to return automatically so as to travel with the next succeeding mold.

In testimony whereof I affix my signature.
ALEX ANDERSON.
